UNITED STATES PATENT OFFICE.

BURT D. STEVENS, OF EVANSTON, ILLINOIS, ASSIGNOR TO MIEHLE PRINTING PRESS & MANUFACTURING COMPANY, OF CHICAGO, ILLINOIS, A CORPORATION OF ILLINOIS.

WORK-SETTING MEANS.

Application filed April 22, 1922. Serial No. 555,948.

To all whom it may concern:

Be it known that I, BURT D. STEVENS, a citizen of the United States, residing at Evanston, in the county of Cook and State 5 of Illinois, have invented certain new and useful Improvements in Work-Setting Means, of which the following is a specification.

This invention relates to printing presses 10 and more particularly to work setting means therefor.

When the type or plate carried by the chase is set on the type bed, it is desirable to definitely set the side register means associated with a transfer table and also properly locate and place the sheet material on the feed table so that when the sheet material is fed, it will be side registered and leave the proper margin on the sheet material 20 after such sheet has received its impression.

To this end one object of the invention is to provide cooperating means whereby with the margin known the pile of stock may be 25 properly placed on the feed table.

Another object is to provide simple, accurate and reliable means for locating and placing sheet material on the feed table in a manner to meet the requirements for successful commercial operation.

These and other objects are accomplished by means of the arrangement disclosed on the accompanying sheet of drawings, in which—

35 Figure 1 is a fragmentary top plan view of a vertical type of printing press embodying my invention; and

Figure 2 is a fragmentary front elevation showing the type, chase and type bed.

40 The various novel features of the invention will be apparent from the following description and drawings, and will be particularly pointed out in the appended claims.

Referring to the figures of the drawings, 45 it will be noted that my invention is illustrated in connection with a vertical type of printing press having a main frame 10, secured to which is a bracket 11 to which is pivotally connected at 12 the feeder frame 50 13. This feeder frame carries a stock feed table 14 from which sheets of material are fed sheet by sheet to a transfer table 15 from which the sheets are removed by the grippers on the impression cylinder 16. The cylinder 16 and type bed 17 carrying the chase

18 and type or plate 19 are given a relative movement during which the impression is made.

Let it be assumed that no margin on the impressed sheet is to be provided, or, in other words, that the impression runs right up to the edge of the sheet. For making the setting for registering from the left side, a sheet will be placed on the transfer table 15 and moved down over the cylinder by hand 65 and placed so that the left-hand edge of the sheet is in line with the left-hand edge of the type or plate 19 and the front edge of the sheet engaging the type. With the sheet in such position the guide member 24 with 70 its support is given its full right-hand movement and is then adjusted to exactly engage the left-hand edge of the sheet or to the reading indicated on the transfer table when the eye follows rearwardly the left-hand 75 edge of the sheet to the scale on the transfer table. In the instance shown, it will be noted that this reading of $8\frac{3}{4}$ on the scale is found near the left-hand side of the transfer table 15. It is now merely necessary to 80 move the left-hand pile guide 20 to the right until the zero mark thereon is in alignment with the left-hand $8\frac{3}{4}$ mark on the scale on the pile table 14, whereupon the sheet material may be placed upon the table 14 and 85 moved forwardly and to the left until its front and side edges engage the front and side guide portions 21 and 22 respectively, of the pile guide 20. The other pile guide member 23 may then be adjusted with respect to the front right-hand corner of the pile. It will be noted that the scales on the transfer table 15 and pile table 14 are offset 90 with respect to each other. This offset is directly related to the lateral right-hand movement of the side guide member 24. It will be understood that the left-hand edge of the sheet material on the pile table 14 will be to the left of the $8\frac{3}{4}$ marking and in engagement with the side pile guide member 95 22 and will be fed forwardly from such position on to the transfer table 15 where such sheet will be acted upon by the side register member for moving the sheet to the right until the left-hand edge of said sheet is located at the $8\frac{3}{4}$ mark on the transfer table 15. It is in such position when the sheet is fed to the cylinder preparatory to the latter having an impression movement with respect to the type. It is seen, therefore, that 100 105 110

the position of the material on the stock pile table can be accurately determined before such material is placed thereon merely by the use of a sheet of material being placed 5 on the transfer table and being lined up with the type.

It is my intention to cover all modifications of the invention falling within the spirit and scope of the following claims.

10 I claim:

1. In printing press work setting means, the combination of a transfer table having a scale thereon, and a feed pile table having a scale thereon having a definite offset relation with respect to said other scale whereby a sheet of material lined up marginally with the type while extending over the scale on the transfer table indicates the position at which the sheet material should be positioned on the pile table.

2. In printing press work setting means, the combination of a transfer table having a scale thereon, side register means for side registering a sheet of material on said table, 25 and a feed pile table having a scale thereon in a definite offset relation with respect to the scale on said transfer table whereby a sheet of material lined up marginally with the type while extending over the scale on 30 the transfer table indicates the position at which the sheet material should be positioned on the pile table, the extent of offset of one of said scales with respect to the other being related to movement of said side register 35 means.

3. In printing press work setting means, the combination of a transfer table having indicating means thereon, side register means for side registering a sheet of material on 40 said table, and a feed pile table having indi-

cating means thereon in a definite offset relation with respect to the scale on said transfer table whereby a sheet of material lined up marginally with the type while extending over the indicating means on the transfer table indicates the position at which the sheet material should be positioned on the pile table, the extent of offset of one of said indicating means with respect to the other being equivalent to movement of said side 50 register means.

4. In printing press work setting means, the combination of a type bed, type carried thereby, a cylinder, a feed table having indicating means, a transfer table to which material is fed from said feed table preparatory to being registered with respect to said cylinder, said transfer table having indicating means with a definite offset relationship with respect to the feed table indicating means whereby a sheet of material lined up marginally with said type while said sheet extends over said transfer table indicates the definite position which stock material is to occupy on said stock table.

5. In printing press work setting means, the combination of a sheet transfer support, and a feed pile support, said transfer support and feed pile support having relative offset indicating means whereby when a sheet 70 of material is lined up marginally with the type in the printing press and is in cooperative association with said sheet transfer support the position of the stock pile on said feed pile support may be accurately determined.

Signed at Chicago, Illinois, this 17th day of April, 1922.

BURT D. STEVENS.
